UNITED STATES PATENT OFFICE.

WILLIAM F. MALLOY, OF PITTSBURG, PENNSYLVANIA.

DESIGN FOR A FRAME FOR MIRRORS, &c.

SPECIFICATION forming part of Design No. 25,039, dated January 7, 1896.

Application filed November 29, 1895. Serial No. 570,562. Term of patent 31 years.

To all whom it may concern:

Be it known that I, WILLIAM F. MALLOY, a resident of Pittsburgh, in the county of Allegheny and State of Pennsylvania, have invented a new and original Design for Frames for Mirrors, &c.; and I do hereby declare the following to be a full, clear, and exact description thereof.

My invention relates to designs for frames, such as for mirrors, &c.

In the accompanying drawing the frame embodying the design is illustrated by a plan or face view.

The frame consists of the inner molding *a*

inclosed by the leaf-like configuration *b*. 15 This leaf-like configuration *b* is composed of the leaves *c* and the leaves *d*, said leaves *d* being curved in such a manner as to be raised above the leaves *c*.

What I claim is—

The design for mirror frames, &c., substantially as shown and described.

In testimony whereof I, the said WILLIAM F. MALLOY, have hereunto set my hand.

WILLIAM F. MALLOY.
